UNITED STATES PATENT OFFICE.

HENRY D. HIBBARD, OF PLAINFIELD, NEW JERSEY.

BALL-MILL OR COMMUNITER PLATE.

971,196.

Specification of Letters Patent. Patented Sept. 27, 1910.

Application filed March 18, 1910. Serial No. 550,112.

To all whom it may concern:

Be it known that I, HENRY D. HIBBARD, a citizen of the United States, residing at Plainfield, in the county of Union and State 5 of New Jersey, have invented certain new and useful Improvements in Ball-Mill or Communiter Plates, of which the following is a specification.

The present improvement relates to ball 10 mills and lining plates therefor, the object of the invention being to provide,—in connection with an improved plate simple in construction and which may be so fastened to the shell that the distortion of the lining 15 made up by these plates will be reduced to a minimum, so that the holding bolts for the plates will be relieved of a large part of the strain thereon due to the tendency of the plates to shift around the shell,—with means 20 for preventing the bowing or bending of the plates in the middle, due to the stretching thereof, especially when such plates are made of unmachinable metal, such for instance as manganese steel, the present invention 25 being an improvement in part upon that shown and described in the contemporaneously pending application of John M. Sherrerd, Serial No. 508,891, filed July 22, 1909, and with which I am familiar.

30 In the drawings accompanying and forming part of this specification, Figure 1 is a view of a part of the shell, partly in section, with some of these improved plates in position; Fig. 2 is a plan view of one of the 35 plates; Fig. 3 is an end view of the plate shown in Fig. 2, looking down thereon; Fig. 4 is a longitudinal sectional view taken in line 4—4, Fig. 2; and Fig. 5 is a cross-sectional view taken in line a—a, Fig. 2.

40 Similar characters of reference indicate corresponding parts throughout the figures of the drawing.

In that class of machines employed in crushing and pulverizing hard materials, 45 such as cement, clinker, gold ores etc., and known as ball mills, ball tube mills, comminuters and the like, the crushing and pulverizing device consists essentially of a cylindrical shell of metal, such as steel or iron, 50 arranged for rotation around a central shaft or other point of support. The shell is provided with a lining, frequently in the form of steps or shelves from which drops the material which is being crushed and the balls 55 or pebbles which do the crushing. The edge

of one shelf or step usually overlaps the edge of the next adjacent shelf or step, and these shelves or steps are sometimes made to extend the full length of the cylinder and are frequently attached to the cylindrical wall 60 of the shell itself by bolts or rivets, these shelves or steps being made either in one or several pieces. When the shelves or steps are secured to the shell by bolts or rivets, which latter usually extend through the shell, especially when these shelves or steps are made of unmachinable metal such as manganese steel, which, owing to its toughness and resistance to abrasive wear, is particularly well suited for this purpose, the shelves or 70 steps tend to distort under the blows of the balls or crushing material and this tends to bring a somewhat greater strain on the bolts than is desirable, this being due in part to the ductility of the metal, which causes it to 75 "flow" to a small extent and change shape, and thus, as stated, the shelves or steps tend to distort under the blows of the balls or crushing material, so that the bolts not only have to hold the plates against the shell, but 80 also have to resist the tendency of the lining to shift around the inside circumference of the shell. The present improvement is therefore intended not only to reduce this distortion of the lining to a minimum and so 85 take the strain off from the holding bolts, but also to prevent the bulging or bending of the plates and thus assist in materially preventing the strain upon the bolts.

In the present embodiment of the invention the shell 2 is provided at intervals around the same, interiorly thereof, with a series of ribs or bars 3 riveted or otherwise secured on the inner wall of the shell. The ball mill or comminuter plate 4, usually provided with a slotted end or heel 5 for the reception of bolts 6, is also provided with a lug or shoulder 7 integral with the plate and located in position to rest against one of the ribs or bars on the shell. The plate is also 90 provided adjacent to its opposite or toe end with openings 8 for the holding bolts or rivets 6. The plates are assembled so that the heel of one overlaps the heel of a companion plate, whereby such juxtaposed ends may be 95 secured to the shell by the same set of bolts. In this position the shoulder or lug of each plate rests against one of the ribs or bars of the shell, whereby the strain on the bolts which secure the lining plates to the shell is 100 105 110

greatly relieved by reason of the fact that any distortion of the plate under the blows of the balls or crushing material will be received by the ribs or bars of the shell instead of by the bolts, especially as the toe ends of the plates are curved outward and so formed between this integral shoulder and the bolts that distortion of the plates tends to more firmly cause the shoulder of each plate to engage its rib, this being due somewhat to the fact that the curved toe end of the plate is spaced from the rib in such a manner that pressure on the working face of the plate causes the shoulder to firmly engage its shell rib.

It has been found in practice, however, especially when the plate is made of manganese steel, which has a tendency to flow or yield under the pounding action of the balls or other pulverizing material, that the plates tend to bow or bend, which, of course, increases the strain upon the holding bolts, and I have discovered that by providing a means which will permit the stretching of the plates laterally this bending or bowing of the plates is avoided, and consequently considerable of the strain removed from the bolts. That is to say, the constant pounding of the balls on the plate tends to stretch the surface transversely and raise it in the middle, and to overcome this I have provided each plate with means for taking up, or compensating for, the stretching action of the plate, and this means consists in the present improvement of a groove or grooves extending lengthwise in the working face of the plates. The number of grooves will depend of course entirely upon the width of the plate. These grooves, a pair of which are illustrated in the plate shown in the drawing, extend from the toe end of the plate toward the heel end, preferably terminating just back of the slotted portion of the heel. In this improvement the plate is provided at the sides of the grooves with a series of parallel recesses 10, forming strengthening ribs 11, while the thickened portion of the plate is also provided with reinforcing ribs 12 formed by chambers 13. These chambers lighten the plate, especially at the thicker portions thereof, while the ribs materially strengthen it.

In practice the bolt holes 8 could be made somewhat elongated if preferred, thereby to avoid strain being brought against the bolts when the plate is straightened out under the blows of the balls or pebbles.

The grooves may be filled with suitable soft metal, such as babbitt or zinc, which will not only act to prevent the material being crushed from entering the grooves, but will not interfere with the stretching action of the plates, since this soft metal, being located between comparatively hard metal, will yield and be compressed. Thus it will

be observed that the working surface of the plate is broken up by one or more grooves, so that the plate, under the pounding action of the balls, will be permitted to stretch or "give" without the bending or bowing up of the plate in the middle, and thus avoiding an extra strain upon the bolts, which otherwise would occur if the plate were bent up in the middle, so that by the provision of these grooves, instead of the plate raising or bending it will remain flat.

I claim as my invention:

1. A one-piece lining plate having means therein comprising a groove or grooves for preventing the bending or bowing of the plate.
2. A one-piece lining plate having means therein for preventing the bending or bowing of the plate comprising one or more lengthwise extending grooves.
3. A one-piece lining plate having in its working face a groove or grooves for preventing the bowing or stretching of the plate and having on its non-working side one or more reinforcing ribs opposite said groove or grooves, the groove or grooves terminating in relatively wide working surfaces at each side thereof.
4. A one-piece lining plate having in its working face means for preventing the bending or bowing of the plate and comprising one or more grooves extending partway through the plate.
5. A lining plate having a toe and a heel and provided with one or more grooves extending partway through the plate for preventing the bending or bowing of the plate, said grooves terminating at the toe.
6. A shouldered, reinforced, one-piece lining plate having therein one or more grooves for preventing the bending or bowing of the plate.
7. A shouldered and reinforced, one-piece lining plate, having in its working face one or more grooves extending partway through the plate lengthwise thereof for preventing the bending or bowing of the plate.
8. A lining plate having a toe and a heel and between said toe and heel a transversely extending shoulder, and having one or more longitudinally extending grooves, each of said grooves being filled with a soft metal.
9. A lining plate having its working face provided with means for preventing the bowing or bending of the plate, said means comprising one or more grooves extending longitudinally of the plate and each of said grooves being filled with a soft metal.
10. A lining plate having a toe and heel and provided with one or more grooves for preventing the bending or bowing of the plate, each of said grooves being filled with a soft metal.
11. A lining plate having a toe and heel, and intermediate said toe and heel a shoulder,

and having in its working side one or more grooves, each of said grooves being filled with a soft metal.

12. In a ball mill, the combination of a shell having a rib or bar secured to the inner wall thereof, and a lining plate bolted to said shell and having a curved portion spaced from said bar and provided with a shoulder adapted to engage said bar thereby to resist the distortion of the lining and relieve the strain on the holding bolts, said plate

also having means for permitting the stretching of the plate and thereby prevent the bending or bowing thereof, said means comprising one or more grooves extending 15 longitudinally of the plate and each of said grooves having soft metal therein.
